PHONOGRAPHIC APPARATUS

Glenn Leslie Dimmick, Westmont, N. J., assignor
to Radio Corporation of America, a corpora-
tion of Delaware

Application February 24, 1933, Serial No. 658,345

11 Claims. (Cl. 274—5)

This invention relates to sound or other impulse recording and reproducing apparatus, and has for its principal object the provision of an improved apparatus and method of operation whereby objectionable noises commonly designated as ground or background noise are minimized or obviated.

It is well known that dust, scratches, finger marks and the like on a photographic sound track tend to produce objectionable noise during the reproduction of the recorded sound. To a lesser extent the same result is produced by the grain of the film upon which the record is made.

Various means of avoiding this difficulty have been proposed and utilized in the past. Among these ground noise eliminating or noiseless recording means, the best known are the biased light valve utilized in the recording of variable density sound track, the biased shutter utilized in the recording of variable area sound track and disclosed in United States Patent No. 1,855,197 of Hugh McDowell, Jr., and the biased galvanometer also utilized in the recording of variable area sound track and disclosed in United States Patents No. 1,854,159 of Lewis T. Robinson and No. 1,853,812 of Clarence W. Hewlett.

In all these known systems of noiseless recording, the sound or other impulses to be recorded are first converted into corresponding electrical impulses and these electrical impulses are utilized to control the operation of the light valve, the light shutter or the galvanometer. For convenience in description, these various systems will be designated as indirect recording systems.

In addition to these indirect recording systems, a limited use has also been made of a direct recording system such as that disclosed by United States Patents Nos. 1,527,649, 1,549,550 and 1,598,377 of Charles A. Hoxie. In accordance with this direct recording system, the acoustic impulses to be recorded are applied directly to a vibratable member or diaphragm and this diaphragm is utilized to modulate the light applied to the light sensitive recording surface which may be of any suitable form such as a moving picture film, a sensitized paper strip, a disk or the like.

While the direct type of recording system has been proposed in various forms and was one of the first to find its way into the art, its use has been negligible due to various difficulties among which is the problem of operating the direct controlled diaphragm in a manner to eliminate ground noise and permit reproduction of the

recorded sound with a high degree of fidelity.

In accordance with the present invention, this difficulty is avoided by the provision of means whereby a bias pressure dependent on the intensity or volume of the recorded sound is applied to the diaphragm of the direct recording apparatus. As hereinafter explained, this pressure biasing means may include a chamber formed at the rear of the diaphragm and provided with a valved outlet or with a plurality of small outlets. The invention, however, is not limited to these particular forms but includes other suitable means for applying to the diaphragm a bias pressure which functions to maintain a minimum of light transmitting area on the sound track positive at all intensities of the recorded sound or other impulses.

A further object of the invention is to provide a sound or other impulse recording system of the direct type which functions to shift the zero line of the recorded impulses in accordance with the intensity, volume or percentage modulation of the recorded sound.

Another object is to provide means for producing a bias pressure which varies in accordance with the intensity of the impulses to be recorded.

The invention will be better understood from the following description when considered in connection with the accompanying drawing and its scope will be pointed out in the appended claims.

Referring to the drawing,

Fig. 1 is a diagrammatic showing of an impulse recording system to which the invention is applied.

Fig. 2 is an explanatory diagram relating to the character of record produced by the system of Fig. 1.

Fig. 3 is a sectional view of the impulse pick-up and diaphragm biasing means which forms a part of the system illustrated by Fig. 1, and

Fig. 4 illustrates a lens mirror or light reflecting element which may form a part of the device of Fig. 3.

The system of Fig. 1 includes a sound pick-up device 10 provided with a light reflecting element 11 which may be in the form of a lens mirror (see Fig. 5). Light is applied to this mirror from a source 12 through a lens 13 and an apertured light stop 14. The light reflected from the mirror 11 is transmitted through lenses 15 and 16 and a light slit block 17 to a light sensitive recording surface 18 which may be the sound track of a moving picture film 19 or the like.

105
110

(see Fig. 2). With this arrangement, the light applied to the sound track 18 is modulated in accordance with the pressure impulses applied to the diaphragm of the pick-up device 10. The 5 manner in which this device functions will be understood upon examination of Fig. 3.

As indicated by Fig. 3, the pressure impulses to be recorded are applied to a diaphragm 20 through a mouth piece 21. Attached to this 10 diaphragm is a drive rod 22 arranged to cooperate with the vibratable support 23 of the mirror 11. It will be observed that this support 23 is pivoted between the drive rod 22 and a support 24 mounted at the back of the device 10 so 15 that the motion of the diaphragm is transmitted to the mirror.

For the purpose of applying to the diaphragm 20 a bias pressure which is dependent on the intensity of the impulses to be recorded, a member 25 having an opening 26 covered by a resilient cover or flap 27 is provided. It will be observed that a resilient washer 28 of rubber or the like surrounds the driver rod 22 and is attached to the member 25 for the purpose of preventing air 20 leakage around the rod.

With this construction, the pressure in the chamber formed between the diaphragm 20 and the member 25 is dependent on the amplitude of the vibrations to which the diaphragm 20 is subjected. Thus when the amplitude of these 30 vibrations is relatively small, little air is ejected from the chamber through the valve 27 and the bias pressure is low. When the diaphragm vibrates through a relatively large amplitude, however, a larger volume of air is ejected through 35 the valve and the biasing pressure is largely due to the fact that air is returned to the chamber at a comparatively low rate. Due to this bias pressure, the zero line about which the diaphragm 40 20 and the mirror 11 are oscillated is shifted so as to maintain the exposed part of the sound at the maximum value permissible without the peaks of the recorded impulses being cut off by the edge of the record track. Under these 45 conditions, the light transmitting area of the positive sound track is maintained at the minimum permissible value and the ratio of ground noise to signal noise is relatively small.

In the form of the invention illustrated, it is 50 necessary that the bias pressure be negative in value due to the direction of rotation of the mirror and the direction of shift necessary. If, however, the position of either the sound track or the mirror support were reversed the direction 55 of bias pressure would have to be also reversed, i. e., made positive, which may be accomplished by reversal of the valve 27. It should be understood, however, that the magnitude and/or variation of the bias pressure may be in 60 either the positive or negative sense in relation to the pressure upon the other side of the diaphragm, although for a given set of conditions the direction or sense of the bias pressure remains the same and the pressure varies only in 65 magnitude.

While the invention has been described as applying to the photographic recording of sound or other impulses it will be readily understood

by those skilled in the art that it is equally applicable to the recording of such impulses by means of a phonograph stylus or the like.

I claim:

1. The method of impulse recording which includes subjecting a vibratable member to the impulses to be recorded, and applying to said member a bias pressure dependent on the amplitude of said impulses. 80
2. The method of impulse recording which includes subjecting a diaphragm to the impulses to be recorded, and applying to said diaphragm a bias pressure which varies in accordance with the amplitude of said impulses. 85
3. The method of sound recording which includes subjecting a diaphragm to the sound to be recorded, and applying to said diaphragm a bias pressure dependent on the volume of said sound. 90
4. The method of sound recording which includes subjecting one side of a diaphragm to the sound to be recorded, and applying to the opposite side of said diaphragm a bias pressure which is dependent on the volume of said sound. 95
5. The method which includes applying to a vibratable member a pressure which is the resultant of the pressure of the impulses to be recorded and a pressure dependent on the amplitude of said impulses, and recording the vibrations of said member. 100
6. The combination of a diaphragm, means forming at one side of said diaphragm a chamber provided with a valved outlet, and sound recording means operable in response to movement of said diaphragm. 105
7. The combination of a diaphragm, means forming at one side of said diaphragm a chamber provided with a valved outlet, and means operable to record the movement of said diaphragm. 110
8. The combination of a diaphragm, means forming at one side of said diaphragm a chamber provided with a valved outlet, and means operable photographically to record the movement of said diaphragm. 115
9. The combination of a vibratable member, means forming at one side of said member a chamber from which a fluid is ejected at a comparatively high rate and to which a fluid is admitted at a comparatively low rate, and means operable in accordance with the vibrations of said member. 120
10. The combination of a vibratable member, means forming at one side of said member a chamber from which a fluid is ejected at a comparatively high rate and to which a fluid is admitted at a comparatively low rate, a drive rod connected to said member, and means responsive to the movement of said rod for recording the vibrations of said member. 130
11. The combination of a vibratable member, means forming at one side of said member a chamber from which a fluid is ejected at a comparatively high rate and to which a fluid is admitted at a comparatively low rate, and means including a mirror coupled to said member for photographically recording its movement. 135
